(57) **CLAIM**

The ornamental design for an external electrical stimulator, as shown and described.

DESCRIPTION

FIG. 1 is a perspective view of the external electrical stimulator in an open position according to our new design; FIG. 2 is a front view thereof;

FIG. 3 is a rear view thereof;

FIG. 4 is a left side view thereof;

FIG. 5 is an enlarged view of area 5 as shown in FIG. 4;

FIG. 6 is an enlarged view of area 6 as shown in FIG. 4;

FIG. 7 is an enlarged view of area 7 as shown in FIG. 4;

FIG. 8 is a right side view thereof;

FIG. 9 is a top view thereof;

FIG. 10 is a bottom view thereof;

FIG. 11 is a perspective view of the external electrical stimulator in an open position and in a position of use, with additional environmental subject matter;

FIG. 12 is a rear perspective view of the external electrical stimulator in an open position and in a position of use, with additional environmental subject matter;

FIG. 13 is a perspective view of the external electrical stimulator in a closed position according to our new design; FIG. 14 is a front view of the external electrical stimulator in a closed position;

FIG. 15 is a rear view of the external electrical stimulator in a closed position;

FIG. 16 is a left side view of the external electrical stimulator in a closed position;

FIG. 17 is a right side view of the external electrical stimulator in a closed position;

FIG. 18 is a top view of the external electrical stimulator in a closed position; and,

FIG. 19 is a bottom view of the external electrical stimulator in a closed position.

The dash-dash broken lines in the drawings are for the purpose of illustrating environmental subject matter that forms no part of the claimed design. The dot-dash broken lines represent the boundaries of the enlarged areas showing the edge of FIG. 4.
